UNITED STATES PATENT OFFICE.

CHAPIN F. LAUDERDALE, OF MILWAUKEE, WISCONSIN.

DENTAL SWAGING-MACHINE.

SPECIFICATION forming part of Letters Patent No. 727,811, dated May 12, 1903.

Application filed March 24, 1902. Serial No. 99,789. (No model.)

To all whom it may concern:

Be it known that I, CHAPIN F. LAUDERDALE, a citizen of the United States, residing at Milwaukee, in the county of Milwaukee and State 5 of Wisconsin, have invented a new and useful Dental Swaging Device, of which the following is a specification.

This invention relates to certain improvements in devices of that class employed for 10 swaging or shaping sheet metal in the formation of crowns and analogous articles in dental work, and has for its principal object to provide a simple, efficient, and inexpensive swaging device in which the various members may be readily separated, the lower die member being arranged in the form of a readily-removable cup or ring, which will permit 15 of the ready interchange of dies or the insertion of artificial teeth.

20 A further object is to so construct the striking member or the upper die member, to which pressure or other force is applied, as to prevent the same from rebounding and displacing the metallic plate being swaged.

25 With these and other objects in view, the invention consists in the novel construction and arrangement of parts hereinafter described, illustrated in the accompanying drawings, and particularly pointed out in the 30 appended claims.

In the drawings, Figure 1 is a sectional elevation of a swaging device constructed in accordance with my invention, illustrating the employment of a cup-like die-receiving body having a tooth-receiving surface or bed 35 of wax-like material. Fig. 2 is a perspective view of said cup member detached. Fig. 3 is a view similar to Fig. 1, illustrating the swaging device as employed in connection with a 40 die formed of cast metal. Fig. 4 is a detail perspective view of such cast-metal die and its holding-ring. Fig. 5 is a sectional view of the die-holding ring, illustrating the method of forming a matrix, a tooth-form being placed 45 on a flat surface at a point within the ring and the latter then filled with fusible material. Fig. 6 is a detached perspective view of the removable plunger or striking member.

Similar numerals of reference are employed 50 to indicate corresponding parts throughout the several figures of the drawings.

10 indicates a cylinder open at both ends

and adapted for the reception of the lower die member 11, which fits snugly within the lower end of the cylinder, the connection being sufficiently close to prevent any lateral movement of the die member, but permitting the separation of the cylinder from the die member when it is necessary to adjust a piece of metal to be swaged or to change the die or 55 matrix.

The die member, as shown in Figs. 1 and 2, is in the form of a cup having a recessed upper surface in which is placed a wax-like body 12, the material employed being hard 60 at ordinary temperature and readily softened by the application of heat, so that it may receive an impression of a tooth-surface and act as a matrix for the swaging of a plate, or it may be employed as a retaining medium 65 in which to embed artificial teeth for the purpose of adapting metal to the surface thereof, the die or matrix being readily changed when necessary.

The lower die member may be provided 70 with a ring 11', as indicated in Figs. 3, 4, and 5, said ring acting as a support for a body 12' of readily-fusible metal, in which a die or matrix may be formed in any suitable manner. A convenient method of forming a 75 matrix from fusible metal is illustrated in Fig. 5, the open-ended ring being placed around a suitable die, such as a tooth or other object, and the fusible metal poured in until the ring is filled, after which the ring is inverted 80 and placed in position in the lower end of the cylinder 10. The cup and ring may be interchanged in accordance with the character 85 of the work to be performed, and as the cylinder and die are readily separated the sheet 90 metal to be swaged may be accurately adjusted in position.

One of the principal objects of the present invention is to provide the upper die member or plunger with a mass of yielding 95 pliable material which will readily conform to the surface of the tooth or other die or matrix and will exert substantially equal pressure on each portion of the surface thereof, thereby swaging the sheet metal accurately to all surfaces whether undercut or otherwise, the die or matrix being firmly supported and the risk of breakage reduced 100 to a minimum. The upper plunger 14 fits

snugly within the upper end of the cylinder and projects thereabove for a sufficient distance to permit it being struck by a mallet, and in its lower face is a recess containing a 5 rubber or other yielding body 15, adapted to conform to the surface of the die or matrix. The lower portion of this rubber-like mass projects below the lower end of the plunger, and its normal diameter if unconfined by the 10 cylinder is greater than the diameter of the plunger, as illustrated in Fig. 6. Owing to the increased diameter of the yielding material and its inherent tendency to spread to its normal or original diameter, the material 15 will press closely against the walls of the cylinder and will hold the plunger in any position to which it may be moved.

With a device constructed in accordance 20 with my invention the plunger may be struck a series of blows by a mallet and will remain in the position to which it is moved after each blow, all tendency to rebound being prevented.

While the construction herein described, 25 and illustrated in the accompanying drawings, is the preferred form of the device, it is obvious that various changes in the form, proportions, size, and minor details of the structure may be made without departing 30 from the spirit or sacrificing any of the advantages of my invention.

Having thus described my invention, what I claim is—

1. A swaging device comprising in combination, a cylinder, a lower die member having a fusible die or matrix member, and a plunger guided within the upper end of the cylinder and having on its lower end a yielding body adapted to conform to said die, said 35 yielding body being arranged partly in a recess in the lower end of the plunger and projecting below the end thereof, the lower portion of said yielding body having an original or normal diameter greater than the bore of 40 the cylinder and when compressed within the cylinder serving as a means for holding the plunger in any position to which it may be adjusted, said die member and plunger being removable from opposite ends of the cylinder.
2. A dental swaging device, comprising in 45 combination, a cylinder, a lower die member

readily removable therefrom, and having a fusible die or matrix member, a plunger guided within the upper portion of the cylinder and having an upper striking-surface 55 above the top of said cylinder, and a yielding body carried by the lower end of the plunger and adapted to conform to the die member, said yielding body being arranged partly in a recess in the lower end of the plunger and 60 projecting below the end thereof, the lower portion of said yielding body having an original or normal diameter greater than the bore of the cylinder and when compressed within the cylinder serving as a means for holding 65 the plunger in any position to which it may be adjusted, said die member and plunger being loosely disposed in and readily removable from said cylinder.

3. A dental swaging device comprising in 70 combination, a cylinder, a lower die member carried thereby, a plunger of a diameter approximately equal to the bore of the cylinder and guided therein, and a yielding body carried by the lower end of said plunger and 75 adapted to conform to the die member, said yielding body being arranged partly in a recess in the lower end of the plunger and projecting below the end thereof, the lower portion of said yielding body having an original 80 or normal diameter greater than the bore of the cylinder.

4. In a device of the class specified, the combination with a cylinder and die, of a plunger adapted to said cylinder, said plunger having a recessed lower end, and a yielding swaging-body arranged in said recess and extending below the end of the plunger, the lower portion of said yielding body having an original or normal diameter greater than the bore of 85 the cylinder and when compressed within the cylinder serving as a means for holding the plunger in any position to which it may be adjusted.

In testimony that I claim the foregoing as 90 my own I have hereto affixed my signature in the presence of two witnesses.

CHAPIN F. LAUDERDALE.
